UNITED STATES PATENT OFFICE.

WILLIAM HOFFMAN, OF BLOOMSBURG, PENNSYLVANIA, ASSIGNOR, BY DIRECT AND MESNE ASSIGNMENTS, TO THE MAGEE CARPET CO., OF BLOOMSBURG, PENNSYLVANIA, A CORPORATION OF PENNSYLVANIA.

YARN-STEAMER.

1,266,265.

Specification of Letters Patent.

Patented May 14, 1918.

Application filed September 30, 1914. Serial No. 864,304.

To all whom it may concern:

Be it known that I, WILLIAM HOFFMAN, a citizen of the United States, residing in Bloomsburg, Columbia county, Pennsylvania, have invented Yarn-Steamers, of which the following is a specification.

My invention consists of an improved apparatus particularly designed for steaming dyed yarn to "set" the dye, one object of said 10 invention being to provide a steamer in which all of the yarn is subjected to the same pressure and the steam supply is kept constant in order to cause the dye to set evenly and to prevent the varied and blurred 15 shades of yarn produced when these conditions are not fulfilled.

Another object of the invention is to provide a steamer which shall be automatic in its operation and thus avoid the necessity 20 for the attendant heretofore employed to regulate the steam supply.

These objects and other advantageous 25 ends I attain as hereinafter set forth, reference being had to the accompanying drawing in which,

The figure is a sectional elevation of my invention.

In the above drawing, 1 is the steaming tank which may be of any suitable construction being shown as a hollow cylindrical structure permanently closed at one end and having a door 2 at the opposite end to permit of the insertion and removal of trucks or cars holding the yarn to be steamed.

35 For the purpose of supplying steam to the interior of the tank 1, I provide a pipe 3 which after passing through its closed end bends downwardly and continues in a section 4 for substantially the entire length of 40 the tank adjacent its bottom. This section has relatively small outlet openings in its upper portion designed to deliver steam throughout the whole length of the tank. A pipe 5 enters the top of the tank 1 and leads 45 to a weighted valve 6 which is employed both as a safety valve, so as to release any abnormal pressure in the tank, as a blow off valve. This valve is so constructed as to permit free communication between the interior of the tank and a diaphragm casing

50 8, through a conduit 7. This latter includes a water sealed trap 9 for preventing flow of steam to the casing 8. The diaphragm in

this latter acts through a rod 10 upon a lever 11 fulcrumed at 12 to a suitable lug 13 projecting from said casing.

The lever 11 is connected through a link 18 with an arm 19 attached to a valve 14 in the main steam supply pipe 3 so that a movement of said arm in one direction will 55 reduce or cut off the steam supply, while the movement in the opposite direction opens said valve to increase the amount of steam passing through the pipe 3 into the tank. The lever 11 carries an adjustable 60 weight 15 whereby the apparatus may be set to cause actuation of the valve 14 whenever a predetermined pressure exists in the casing 8 and hence in the tank. Different pressures may therefore be maintained within 65 the tank 1 by properly moving this weight and for any given pressure steam will be delivered at a substantially constant rate.

In addition to maintaining a constant supply of steam to the tank 1 my invention 70 provides means for causing a circulation of the live steam within said tank, and in addition prevents condensation of the steam to a large extent. This means consists of a bleeding conduit or pipe 16 leading from 75 the top of the tank 1 at or immediately adjacent the middle, and a valve 17 is mounted in said pipe 16 for regulating the amount of steam escaping to suit different conditions either as to the character of the yarn being 80 steamed or to the amount of steam entering 85 the tank 1. The pipe 16 may open directly into the atmosphere or into a condenser and is preferably of a diameter considerably smaller than that of the supply pipe 3 and 90 of the aggregate openings in said pipe. It may however be of any diameter and the valve 17 may be regulated to allow the proper amount of steam to escape.

In order to remove any water which may 95 condense in the bottom portion of the tank 1, I provide an outlet pipe having a water seal or trap 20, whose inner end is substantially flush with the bottom of the tank 1, while its outer end is lower than said tank. 100 A valve 21 is connected in said outlet pipe and serves to regulate the amount of water discharged.

In using my invention the racks of yarn 105 are placed in the tank 1, in such position that all of the yarn is above the perforations

or outlets of the pipe 4 so that the steam passing upwardly in the tank will penetrate the skeins of yarn. After the yarn is in position, the door 2 is closed and steam is admitted through the pipe 3. When the pressure in the tank 1 rises to the predetermined point for which the regulator 8—10—11 is set, as determined by the position of the weight 15, the rod 10 and lever 11 is raised thus partially or wholly closing the valve 14 through the link 18 and arm 19. The pressure in the tank is thus prevented from rising higher and is maintained at the predetermined point by the automatic operation above noted.

The pipe 16 allows a continuous escape of the steam from the tank 1 so that the latter is kept at a relatively high temperature by the continuous supply of live steam from the pipe 3. This feature is particularly valuable since condensation of the steam within the tank is in a great measure prevented and there is an active circulation of the steam

which insures its even and thorough penetration of the yarn.

I claim:—

The combination in a steamer of a tank; a steam supply pipe connected to said tank; a valve in said pipe having an operating arm; a diaphragm casing; a conduit including a water sealed trap connecting said casing to the tank; a weighted lever actuated by the diaphragm of said casing; and means for connecting said lever to the valve operating arm of the steam pipe; with a bleeding conduit; and a valve in said conduit for regulating the amount of steam escaping therethrough.

In testimony whereof, I have signed my name to this specification, in the presence of two subscribing witnesses.

WILLIAM HOFFMAN.
